CLAIM

The ornamental design for a video conference terminal, as shown and described.

DESCRIPTION

FIG. 1 is a front top perspective view of a video conference terminal showing my new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 of FIG. 3;

FIG. 10 is an enlarged portion view taken from encircled portion labeled, “FIG. 10,” in FIG. 2; and,

FIG. 11 is an enlarged portion view taken from encircled portion labeled, “FIG. 11,” in FIG. 2.

The dashed-dot lines form the boundary of the enlarged portion views of FIGS. 10 and 11 in FIGS. 2, 10 and 11 and form no part of the claimed design. The even dashed broken lines shown in the drawings are included for the purpose of illustrating portions of the video conference terminal that form no part of the claimed design.
